UNITED STATES PATENT OFFICE.

ALFRED EDWARD LAYCOCK, OF MOOSOMIN, CANADA.

RADIATOR.

SPECIFICATION forming part of Letters Patent No. 716,906, dated December 30, 1902.

Application filed March 24, 1902. Serial No. 99,568. (No model.)

To all whom it may concern:

Be it known that I, ALFRED EDWARD LAYCOCK, a subject of the King of Great Britain, residing at Moosomin, county of Assiniboia, 5 North-West Territories, Canada, have invented certain new and useful Improvements in Radiators; and I do hereby declare that the following is a full, clear, and exact description of the invention, such as will enable others 10 skilled in the art to which it appertains to make and use the same.

My invention relates to an apparatus intended to be placed in the flues of stoves, furnaces, or other heating appliances to economize 15 the heat of the waste gases therein by delivering it in the form of hot air into an apartment or room and likewise to radiate the heat therefrom, so as to assist in heating said room.

My improved radiator is adapted either to 20 be used in addition to the stove in the same apartment therewith and immediately therover, whereby to increase the capacity of the stove for heating the apartment, or it may be placed in an upper apartment through which 25 the flue-pipe of the stove is carried and whereby the stove is enabled to heat simultaneously two apartments without any additional appliances, such as hot-air and cold-air boxes, registers, steam-circulating means 30 and the like, which greatly add to the expense of heating a house.

My invention consists, essentially, in an enlargement of the stovepipe comprising a peculiar arrangement of concentric cylindrical 35 or annular chambers, which are adapted alternately to contain the smoke or flue gases and to form circulating passage-ways through which the air of the room is adapted to pass.

My invention further consists in the peculiar 40 combination and construction of parts hereinafter more specifically set forth, and which will be particularly pointed out in the claims.

In the drawings forming a part of this specification, Figure 1 represents a vertical cross-section through a house, showing a stove with my improved radiator in the flue-pipe thereof in elevation. Fig. 2 is a central longitudinal sectional elevation of my improved radiator as usually mounted, and Fig. 3 is a 45 similar view showing my improved radiator as reversely mounted and provided with an

attachment particularly fitting it for use with hard-coal fuel.

The same numerals of reference denote like 55 parts in all the figures of the drawings.

That portion of the house shown in the drawings consists of portions of two apartments—to wit, a lower apartment 4 and an upper apartment 5, separated by a floor 6 and inclosed by walls 7—the house being supported upon a foundation 8. The stove adapted to heat the lower apartment is indicated at 9, and it has a vertical flue-pipe 10, extending upwardly through the floor 6 and into the 65 upper apartment 5, and in that part which extends through the apartment 5 is provided my improved radiator, (designated by the numeral 11.) As herein shown, this radiator comprises a cylinder of sheet-iron 12, considerably exceeding the diameter of the stove-pipe and connected therewith by reduced 70 conical ends 13, having parallel flanges 14, into which the ends of the stovepipe 10 telescope. In the interior of this sheet-iron cylinder 75 is located a similar but smaller concentric cylinder 15, which is solidly connected to the outer cylinder by a pair of short cylindrical openings 16 at opposite extremities of a diameter located at the upper end, and 80 a similar pair 17, located at the lower end thereof, thus connecting interiorly the cylinder 15 with the exterior of the radiator, while separating both from the intermediate annular space 18. Within the cylinder 15 there 85 is another concentric piece 19, herein shown as somewhat conical in form, and tapering smaller toward the top, as I have found this form gives improved results in a manner which will be stated presently. This cone 19 90 is of slightly less length than the cylinder 15 and is connected therewith at top and bottom by dished annular plates 20 21, respectively, thus forming an annular closed chamber 22 between the cylinder 15 and cone 19 of 95 roughly quadrangular section, which chamber is connected with the outside air of the apartment by the apertures 16 and 17, as above mentioned. The inner conical space 23, formed within the cone 19, is subjected 100 to the action of the flue-gases which pass therethrough, and its upper end is suitably closed by a damper in the form of a butterfly-valve 24, having a shaft 25, which is piv-

95

100

oted at 26 in the walls of the cone 19 and extends upwardly through one of the apertures 16 and is provided with a cross-bar 27 to form a handle for turning the valve.

5 The flue-gases in passing up through the flue-pipe 10 impinge upon the dished plate 21 and are separated into two portions, one passing around through the annular chamber 18 and the other passing up through the conical chamber 23, and in both cases they part with a portion of their heat to the outside air of the apartment and to that which circulates in the air-chamber 22. These two portions of the flue-gases again join one another in 15 the upper cone 13 of the radiator and pass out through the continuation of the flue-pipe 10, as indicated by the arrows. The air-inlets 17, being separated by a quarter-circle from the air-inlets 16, cause more thorough circulation of the air through the inner chamber 22 than if they were located one above the other.

In Fig. 3 I have shown precisely the same device as in Fig. 2, and it is accordingly indicated by the same reference-numerals; but I have also shown in addition a funnel-shaped member 28, which is inserted through the upper end of the radiator within the flue-pipe, as I have found this arrangement specially 30 advantageous when hard coal is burned in the stove, because it causes a longer period of radiation and more thorough circulation of the flue-gases around the air-chamber 22 than where the upper end of the chamber 23 is simply open. This therefore illustrates the fact that my improved radiator is reversible, and its two opposite positions are suitable for different conditions, as will be found by experience.

40 The object in having the plates 20 21 dished or concave is that it greatly strengthens the air-box in the flue and prevents warping or distortion of the metal in great heat.

While I have shown in the accompanying drawings the preferred form of my invention, it will be understood that I do not limit myself to the precise form shown, for many of the details may be changed in form or position without affecting the operativeness or 45 utility of my invention, and I therefore reserve the right to make such modifications as

are included in the scope of the following claims.

Having thus described my invention, what I claim as new, and desire to secure by Letters Patent, is—

1. A flue-radiator comprising a cylindrical casing having conical ends adapted to telescope into the flue, an air box or chamber supported therein having a concentric cylindrical outer wall, a concentric conical inner wall and dished annular end plates, a pair of passages forming supporting means for the air-chamber at opposite extremities of a diameter connecting the interior of the air-chamber with the outside air and at one end thereof, another pair of passages connecting the interior of the air-chamber with the outside air at the other end thereof, the last-named pair of passages being at an angular distance of ninety degrees from the first-named pair, and a damper operated by a handle extending through one of said passages, said damper closing the interior passage for the flue-gases.

2. A flue-radiator comprising a sheet-metal cylinder having conical reduced ends, an annular cylindrical air-box supported concentrically in said cylinder whereby to divide the flue-gases into two portions, a damper closing the inner passage-way for the flue-gases, circulating-apertures connecting the interior of the air-box with the outside air, and a funnel-shaped pipe depending from the upper end of said radiator.

3. A flue-radiator comprising a cylindrical casing adapted to form a portion of a flue, an air box or chamber supported therein having a concentric cylindrical outer wall, a concentric conical inner wall tapered from top to bottom and dished or concaved annular end plates connecting said walls, in combination with a conical baffle-tube suspended from the upper end of the casing and depending within said inner conical wall and having its sides approximately parallel thereto, substantially as described.

In witness whereof I have hereunto set my hand in the presence of two witnesses.

ALFRED EDWARD LAYCOCK.
